UNITED STATES PATENT OFFICE.

LOUIS PLEIN, OF CHICAGO, ILLINOIS.

INTERNAL-COMBUSTION ENGINE.

1,278,009.

Specification of Letters Patent. Patented Sept. 3, 1918.

Application filed February 23, 1917. Serial No. 150,482.

To all whom it may concern:

Be it known that I, LOUIS PLEIN, a subject of the Grand Duchy of Luxemburg, who have declared my intention of becoming a citizen of the United States, and a resident of the city of Chicago, county of Cook, and State of Illinois, have invented certain new and useful Improvements in Internal-Combustion Engines, of which the following is a specification.

My invention relates to improvements in internal combustion engines and has for its object the provision of an improved construction of this character capable of operating with great efficiency.

The invention consists in the combinations and arrangements of parts hereinafter described and claimed.

The invention will be best understood by reference to the accompanying drawing forming a part of this specification, and in which,

Figure 1 is a vertical section of an engine, embodying my invention,

Fig. 2, an enlarged section taken on line 2—2 of Fig. 1, and

Fig. 3, an enlarged section taken on line 3—3 of Fig. 1.

The preferred form of construction as illustrated in the drawings comprises a suitable outer casing 4 having a crank shaft 5 mounted in the lower portion thereof and a cylinder 6 in the central and upper portion, as indicated. A piston 7 operates in cylinder 6 and is connected with crank shaft 5 by means of a connecting rod 8. One end 9 of the crank shaft 5 is connected by means of a belt or chain 10 with a timer shaft 11 in turn connected by a belt or chain 12 with an operating shaft 13, traversing the upper or outer end of the cylinder 6. The shaft 13 is provided with two angularly positioned crank pins 14 each connected by means of a connecting rod 15 with a yoke 16 secured to the upper ends of a corresponding pair of valve operating rods 17 sliding through the head of cylinder 6. One pair of rods 17 is connected with an intake valve 18 and the other pair of said rods with an exhaust valve 19 operating in cylinder 6. This connection is effected by means of radial T-slots 20, in the outer or upper ends of said valves, and corresponding members 21 on the inner ends of the rods 17, this arrangement effecting a simple and positive connection and one which may be assembled

or taken apart. The valves 18 and 19 operate in a valve space 22 formed between an inwardly projecting cooled head 23 and the walls of cylinder 6, as shown. Valves 18 and 19 are semi-cylindrical in form and hollow, with the inner ends of the hollow portions opening into the cylinder 6. Valve 18 is provided with an annular intake port 24 adapted to register with the upper of two intake ports 25 formed in the walls of cylinder 6. Likewise valve 19 is provided with an annular port 26 adapted to register with the upper of two exhaust ports 27 formed in the walls of cylinder 6. A suitable spark plug 28 is arranged in the wall of cylinder 6, as indicated.

The arrangement is such that at each intake the port 24 in valve 18 registers with the upper port 25 at the same time the lower port 25 is uncovered by the valve 18, thus permitting of the passage of the charge through both ports 25 into the cylinder 6. Likewise port 26 registers with the uppermost port 27 when the lowermost port 27 is uncovered by valve 19, permitting of a double exhaust. By this arrangement free intake and exhaust are obtained thus insuring full charging of the engine and complete exhausting of the same. The arrangement is also such that the force of the explosions in the cylinder 6 assists in the operation of the valves 18 and 19, thus tending to conserve the energy produced by the engine. The water cooled head 23 serves to keep the valves 18 and 19 properly cooled to promote efficiency. The specific form and arrangement of the parts is a simple and efficient one for the purpose.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters Patent is:

1. An internal combustion engine, comprising a cylinder; a piston operating therein; ports in said cylinder; and semi-cylindrical hollow valves operating in said cylinder, said valves being open at their inner ends

and in open connection with the cylinder, and provided with ports in their outer walls co-operating with the cylinder ports to permit passage through said valves, substantially as described.

2. An internal combustion engine comprising a cylinder; a piston operating therein; two intake and two exhaust ports in said cylinder; and semi-cylindrical hollow valves operating in said cylinder, said valves being open at their inner ends and in open connection with the cylinder, and provided with ports co-operating with said cylinder ports to permit the passage of intake and exhaust gases through said valves, substantially as described.

3. An internal combustion engine comprising a cylinder; a piston operating therein; ports in said cylinder; reciprocatory valves in said cylinder controlling said ports; an operating shaft traversing the outer end of said cylinder; connecting rods operatively connected with said valves and sliding through the cylinder head, there being dove-tail connections between said rods and said valves; and operative connections between said rods and said operating shaft, substantially as described.

4. An internal combustion engine comprising a cylinder; a piston operating therein; ports in said cylinder; reciprocatory hollow semi-cylindrical valves in said cylinder controlling said ports; an operating shaft traversing the outer end of said cylinder; connecting rods operatively connected with said valves and sliding through the cylinder head, there being dove-tail connections be-

tween said rods and said valves; and operative connections between said rods and said operating shaft, substantially as described. 40

5. An internal combustion engine comprising a cylinder; a piston operating therein; ports in said cylinder; reciprocatory valves in said cylinder controlling said ports; an operating shaft traversing the outer end of said cylinder; a pair of connecting rods having a dove-tail connection with each of said valves and sliding through the head of said cylinder; a yoke carried by each pair of said rods; and an operative 45 connection between each of said yokes and said operating shaft, substantially as described. 50

6. An internal combustion engine comprising a cylinder; a piston operating therein; ports in said cylinder; reciprocatory hollow semi-cylindrical valves in said cylinder controlling said ports; an operating shaft traversing the outer end of said cylinder; a pair of connecting rods having a dove-tail 55 connection with each of said valves and sliding through the head of said cylinder; a yoke carried by each pair of said rods; and an operative connection between each of said yokes and said operating shaft, substantially as described. 60

In testimony whereof I have signed my name to this specification in the presence of two subscribing witnesses.

LOUIS PLEIN.
